UNITED STATES PATENT OFFICE.

CHARLES S. DEAN, OF FAIRMONT, WEST VIRGINIA.

STEEL MINE TIE.

Application filed February 25, 1924. Serial No. 695,041.

To all whom it may concern:

Be it known that I, CHARLES S. DEAN, a citizen of the United States, residing at Fairmont, in the county of Marion and State of West Virginia, have invented certain new and useful Improvements in Steel Mine Ties, of which the following is a specification, reference being had therein to the accompanying drawing.

10 This invention relates to certain new and useful improvements in steel mine ties especially adapted to be used for laying tracks in mines, the object being to provide a tie which is very durable and one in which 15 a temporary or permanent track can be laid quickly.

Another object of the invention is to provide a tie which is so constructed that the proper gauge is obtained by constructing 20 the ends of the tie with portions to engage the web whereby old and worn out rails can be used and a true gauge maintained.

Another and further object of the invention is to provide a tie with a novel 25 form of keeper which is adapted to be driven into engagement with the rail so as to hold the same securely, said keeper being so constructed that it can be turned around and used for holding the jumper rail securely in place.

Another and further object of the invention is to provide a tie which is exceedingly simple and cheap in construction, the parts being so connected that it is impossible 30 for them to be misplaced when not in use.

Other and further objects and advantages of the invention will be hereinafter set forth and the novel features thereof defined by the appended claim.

40 In the drawings.

Figure 1 is a side elevation partly in section of a tie constructed in accordance with my invention showing the rails and a jumper rail in position;

45 Figure 2 is a top plan view, the rails being shown in section; and

Figure 3 is a detail elevation, partly in section, of a slightly modified form of tie especially adapted to be used upon a permanent track.

50 In carrying out my invention I construct the tie out of a piece of channel steel with the edges of the channel extending downwardly as clearly shown in order to imbed themselves in a road-bed to prevent the tie from moving.

The ends of the channel bar 1 from which the tie is formed are bent upwardly and inwardly as shown at 2 to form hooks adapted to embrace the outside bases of the rails 3, the extreme ends being bent upwardly into vertical position as shown at 4 to engage the web of the rails whereby a tie formed to a proper gauge will hold the rails 3 to a true gauge irrespective of the worn condition of the rails used in forming a track.

Pivotedly mounted adjacent each end of the rail are keepers 5 and 6 herein shown mounted on rivets 7 and having end portions 8 and 9 extending upwardly to embrace the inside bases of the rails 3, said portions terminating in vertical portions 10 and 11, which are provided with rounded faces 12 in order to allow these faces to be driven against the inner faces of the webs of the rails to force said rails against the vertical portion 4 of the tie so as to lock the rails securely in position.

The other ends of the keepers are rounded as shown at 13. These keepers are so mounted that after the rails have been placed in position with the keepers swung at right angles to the tie, they can be swung on the pivots and driven with an axe or sledge hammer into the position shown in Figures 1 and 2.

In Figures 1 and 2, I have shown a jumper rail 14 disposed at one end of the tie with the keeper 6 swung into a reverse position so that the rounded end 13 is brought into engagement with the base of the keeper rail 14 in order to force the head of the rail against the web of the adjacent rail 3 in order to lock said jumper rail in position.

It is, of course, understood that when a jumper rail is not used, the rounded ends 12 of the keepers are forced into engagement with the web of the rails and by this particular construction, the same keeper can be used to lock the rails forming the track in position on the tie or a jumper rail in connection with the usual rails, as by the particular construction of keeper and the position of the same, either one of the keepers can be reversed and a jumper rail placed in position on the tie and secured, said jumper rail also holding the adjacent rail in position on the tie.

In Figure 3 I show a channel tie 15, the end of which is bent back upon itself as shown at 16 and then upwardly as shown at 17 to engage the base of the rail, then ver-

2
tically as shown at 18 to engage the web of the rail, said tie being provided with a keeper 19 constructed substantially in the same manner as shown in Figures 1 and 2. 5 The portions 16 of the end of the tie which is bent back upon itself, are secured together by a rivet 20 and this provides a tie with an extension at its end to increase the length of the tie to provide a tie which can be used 10 on an ordinary railroad.

It might be found of advantage in some instances to use such a construction of tie in connection with a mine track and therefore I do not wish to limit myself to either 15 form as my invention consists in forming a channel tie with a portion bent in such a position that it has a web-engaging portion to hold the rail at a true gauge in connection with the particular construction of 20 keeper which is reversible.

From the foregoing description it will be

seen that I have provided a rail tie formed of a piece of channel steel with the flanges of the channel extending downwardly with its ends bent to engage base and web receiving portions of the rails in connection with a novel form of keeper which can be driven into set position so as to hold the rails in true alignment and at the proper gauge.

What I claim is:—

A tie formed of a single piece of channel iron having hooked ends to engage the base and web of rails, keepers pivotally mounted on said tie having portions to engage the 35 base and web of rails, said keepers being reversible for securing a jumper rail in position against one of the adjacent rails supported by said tie.

In testimony whereof I hereunto affix my 40 signature.

CHARLES S. DEAN.
